UNITED STATES PATENT OFFICE.

CHARLES R. LAW, OF HOUSTON, TEXAS.

CAR JOURNAL-BOX.

1,196,553.

Specification of Letters Patent. Patented Aug. 29, 1916.

Application filed August 5, 1913. Serial No. 783,022.

To all whom it may concern:

Be it known that I, CHARLES R. LAW, a citizen of the United States, residing at Houston, in the county of Harris and State 5 of Texas, have invented certain new and useful Improvements in Car Journal-Boxes, of which the following is a specification.

This invention relates to new and useful 10 improvements in car journal boxes, and more particularly to the box in which the journal of the axle of the ordinary railway car has a bearing.

The object of the invention is to provide a 15 box of the character described whose outer end is completely inclosed and whose entrant opening to the interior of the box is on the side thereof. In the ordinary axle box the entrant opening to the interior thereof is at the outer end and is protected by a 20 door or covering but when used on cars for carrying logs or other heavy articles which are loaded on to the cars ordinarily by means of lifting cranes, the protecting doors of the boxes are often broken from the boxes by 25 reason of the fact that the heavy article in being swung into position upon the cars strikes against the outer ends of said boxes, thereby breaking and dislocating said doors and leaving the interior of the boxes un- 30 protected against the entrance of sand and other foreign matter. It is the chief object of this invention to obviate this defect.

Another object of the invention is to provide a box of the character described so constructed that the impact of said heavy articles against the outer end of the box, in the process of loading, will be received by the outer end of the axle, thus preventing the inner side of the box from impacting against 40 the car wheel and injuring or breaking said inner side of the box.

Another object of the invention is to provide a box of the character described so constructed that easy access may be had to the 45 interior thereof for the purpose of removing and replacing the journal bearing and for the further purpose of applying lubricating means to the journal.

With the above and other objects in view, 50 the invention has particular relation to certain novel features of construction and arrangement of parts, an example of which is given in this specification, and illustrated in the accompanying drawings, wherein—

55 Figure 1 shows a front view of the trucks of a car, the axle of which is journaled in

my improved form of box. Fig. 2 is an end view of the box. Fig. 3 is a sectional end view thereof. Fig. 4 is a side elevation thereof. Fig. 5 is a vertical sectional view 60 thereof. Fig. 6 is a plan view thereof. Fig. 7 is a plan view of the door protecting the side opening of the box, and Fig. 8 is an end view thereof.

Referring now more particularly to the 65 drawings, wherein like numerals of reference designate similar parts in each of the figures, the numeral 1 refers to the axle to which the wheels 2 are fixed. The axle 1 extends each way beyond the wheels and 70 said projecting ends are formed into journals, as 3. The journal box 4 is substantially square in cross section and in general contour is of the usual form. The box is cast hollow and with its inner end open and the journal 3 of the axle extends through 75 said open end into the interior of the box. The outer end of the box is entirely closed and the outer end of the journal 3 is spaced only a short distance from the outer end of 80 the box so that any impact received by the outer end of the box will be sustained by the axle journal and the inner end of the box thus protected against impact against 85 the car wheel.

The numeral 5 refers to the bearing for the journal 3. This bearing is usually formed of brass and in cross section is arch-like in form, the under side thereof being 90 concaved so as to fit upon the journal 3, as shown in Fig. 3.

One side of the box 4 has an oblong opening for the purpose of permitting access to the interior of the box. This opening is protected by a removable covering 7 which 95 is an oblong, thin, metallic plate. This plate is held in position by means of a strong flat spring 8 which is pivoted at its center to the center of the covering 7 and whose ends engage in arcuate grooves 9, 9 at opposite ends of the box and when so engaged hold said covering in position. The spring 8 may be swung around on its pivotal support so as to disengage its ends from said grooves 100 when it is desired to remove said covering. Any other method, however, of securing the covering in position may be employed. The boxes of the different trucks are fixed in position relative to each other by means of iron bars or straps, 9', 9', above and below 105 and lugs 10', 10' project out from the bottom and top of the box 4 above and below the

door 7 and the ends of the bars 9', 9' are secured to said lugs by means of short bolts 11', 11', as shown in Fig. 1. In the usual form of construction, one long bolt is used 5 for each box instead of two short ones, said bolt extending through both straps 9', 9', so as to clamp them above and below the box, but I have provided the two short bolts and the lugs 10', 10' so that there will be no 10 obstruction to prevent or interfere with the free removal of the door 7, or its replacement in position. It is further to be observed that the oblong opening at the side 15 of the box 4, and which is closed by the door 7, is at the upper side of the box, as is more clearly indicated in Fig. 3, so that the bottom of the box will form a lubricant receptacle and there will be no liability of the lubricant escaping through the side opening 20 of the box. Integral with the inner face of this covering and extending inwardly therefrom is an oblong lug 10 and projecting inwardly from the opposite side of the box 4 and integral therewith is a similar 25 lug 11, the said lugs 10 and 11 embracing the bearing 5 on each side and holding the same in position above the journal 3.

The numeral 12 refers to a dust guard 30 having a central orifice through which the journal 3 extends. This guard is a thin, flat body composed of woody or fibrous material and is provided to close the inner end of the box and protect the interior thereof from dust and foreign matter, as well as to 35 prevent the escape of the lubricant from the interior of the box. This guard fits down into a groove 13 which extends around the inner wall of the inner end of the box and has free vertical play in said groove.

40 When it becomes necessary to remove or replace any of the internal parts of the box or to lubricate the same, the covering 7 may be removed as hereinbefore described. The box 4 is then jacked up by means of the ordinary lifting jack, relative to the axle, the internal chamber of the box being sufficiently large to permit this relative movement of said box and axle. Access is thus gained to the interior of the box and the 45 bearing 5 and wedge 6 may be adjusted, removed, or replaced as circumstances may 50

require, and the box otherwise adjusted or lubricated as may be found necessary. As the box 4 is moved up or down relative to the axle, the guard 12 slides up and down in 55 the groove 13 but at all times blocks the opening through the inner end of the box into the interior thereof and prevents the entrance of sand and foreign matter into the interior of the box and also prevents the 60 escape of the lubricant-retaining waste with which the internal chamber of the box is ordinarily filled.

What I claim is:—

In a device of the character described, the 65 combination with a car axle of a box having an internal chamber, the inner end of said box being completely open, said end being enlarged and having an internal groove therein, a dust guard carried by said 70 box and located in said groove through which the axle journal passes for closing said open end, said dust guard forming an inclosed reservoir with the bottom of said box and the opposite end of said box being 75 entirely closed and being an integral part thereof, one side of said box being provided with an oblong entrant opening arranged therealong near the top of the box, a closure for said opening, a flat spring bar for 80 resiliently securing said closure in position over said opening, a detachable bearing member within the box and forming a bearing for the axle journal, one inwardly projecting lug carried by the door and an inwardly projecting lug fixed to the opposite side of the box, said lugs resting against the opposite sides of the bearing member and holding it in position, said entrant opening being provided through which said bearing 85 member may be removed and replaced, lugs projecting from the side of said box above and below said entrant opening, said lug being provided to receive the securing means whereby said box is fixed in position. 90

In testimony whereof I have signed my name to this specification in the presence of two subscribing witnesses.

CHARLES R. LAW.
